INVENTOR
HENRY A. WAHLERT
BY *John M. Ladd*
ATTORNEY

UNITED STATES PATENT OFFICE

HENRY A. WAHLERT, OF ST. LOUIS, MISSOURI, ASSIGNOR TO THE AMERICAN BRAKE COMPANY, OF ST. LOUIS, MISSOURI, A CORPORATION OF MISSOURI

BRAKE CYLINDER

Application filed September 3, 1929. Serial No. 389,915.

This invention relates to the mounting of brake cylinder devices to the bed frame of railway locomotives.

Heretofore, in building up a brake cylinder device in the bed frame of the locomotive, it has been the practice to tightly fit a cylindrical bushing in a cylindrical portion of the bed frame to form the body of the brake cylinder. After the bushing was thus mounted, the usual piston and piston rod and other parts of the device were inserted in the bushing and the pressure head and non-pressure head drawn tight against the opposite ends of the bushing by means of nuts having screw-threaded connections with studs anchored in the bed frame. This method of forming the brake cylinder has been found objectionable in that it is difficult, and requires considerable time and labor, to fit the brake cylinder bushing in the bed frame and that it is difficult to obtain a suitable air tight bushing.

The principal object of my invention is to provide a brake cylinder which may be easily assembled with the locomotive bed frame and which will be free from the above mentioned objectionable features.

Other objects and advantages will appear in the following more detailed description of the invention.

In the accompanying drawing, Figure 1 is a plan view of a portion of a locomotive bed frame embodying my improved brake cylinder mounting; Fig. 2 is a side elevational view of the same; Fig. 3 is a cross sectional view on the line 3-3 of Fig. 2; Fig. 4 is an enlarged detail bottom plan view of a portion of the frame, the brake cylinder parts being removed; Fig. 5 is an enlarged fragmentary sectional view showing a modification of the means for securing the pressure head of the brake cylinder to the body thereof and for securing both to the bed frame of a locomotive, and Fig. 6 is a like view illustrating a modification of the means for securing the non-pressure head of the brake cylinder to the bed frame.

As shown in the drawing, the locomotive bed frame may comprise a single integral casting having, at desired locations throughout its length, integral vertically disposed an-

nular walls 1, each of which defines a recess having open ends, which recess is adapted to receive the body portion 2 of a brake cylinder device.

The body portion 2 is cylindrical in form and is of such a diameter that it will have a slip fit with the wall 1 so that it may be inserted in its receiving recess and properly positioned without having to drive it into the bed frame.

The upper end of the portion 2 is provided with an outwardly directed horizontally disposed annular flange 3 having a plurality of openings formed therein through which studs 4, having screw-threaded connection with the wall 1 of the bed frame, extend when the portion 2 is in its proper position in the bed frame. When the portion 2 is positioned, the flange 3 engages the upper end of the wall 1 and prevents undue downward movement of the portion relative to the bed frame.

The brake cylinder device also comprises a pressure head 5 having a plurality of openings through which the studs 4 also extend. This head is clamped tight against the portion 2 by nuts 6 having screw-threaded connection with the upper ends of the studs 4.

The brake cylinder device further comprises a non-pressure head 7 having a plurality of openings through which bolts 8, anchored in the wall 1, extend, the head being clamped tightly to the portion 2 by nuts 9 having screw-threaded connections with the lower ends of the bolts 8.

In Fig. 3 of the drawing, the upper ends of the bolts 8 are shown as being of T-shape and are received within a recess 10 formed in the wall 1. Openings into this recess and formed in the bed frame are notches or slots 17 having open inner ends, which slots are adapted to receive the shanks of the bolts 8 and are each of such a width that the heads of the bolts cannot pass therethrough. Before the portion 2 is positioned, the bolts 8 are positioned as shown, so that when the portion 2 is mounted in the frame, the bolts will be prevented from moving out of engagement with the bed frame.

As shown in Fig. 5 of the drawing the pressure head may be clamped in place through

the medium of bolts 8 and nuts 9 instead of through the medium of the studs 4 and nuts 6.

Further, as shown in Fig. 6, the non-pressure head may be clamped in place through the medium of studs 4 and nuts 6 instead of through the medium of the bolts 8 and nuts 9.

Contained in the brake cylinder is the usual piston 11 having a piston rod 12 attached thereto, the lower end portion of the rod extending through a central opening in the non-pressure head and being operatively connected to a brake lever 13 through the medium of a push rod 14. Also contained in the brake cylinder and interposed between the piston 11 and the non-pressure head 7 is the usual release spring 15. Attached to the piston 11 and clamped between the portion 2 and the non-pressure head 7 and the cylindrical portion 2 is a filter device 16 for extracting foreign matter from the air which enters the non-pressure side of the brake cylinder through the space between the piston rod and the non-pressure head.

From the foregoing description it will be seen that the several parts of the brake cylinder device may be made and fitted together by a manufacturer of such devices, then shipped to the user, and finally built into a locomotive bed frame or the like. Since the manufacturer can supply all of the parts of the brake cylinder device they will not have to be altered in mounting them on the bed frame, thus rendering it possible to assemble the brake cylinder device with the bed frame in less time and with less labor and with more accuracy than has heretofore been possible.

While one illustrative embodiment of the invention has been described in detail, it is not my intention to limit its scope to that embodiment or otherwise than by the terms of the appended claims.

Having now described my invention, what I claim as new and desire to secure by Letters Patent, is:

1. The combination with a vehicle frame having an opening therein, of a brake cylinder device comprising a cylindrical portion insertable in said opening, a flange on said cylindrical portion in supporting engagement with said frame, a pressure head clamped against said flange, and a non-pressure head clamped against said cylindrical portion.

2. The combination with a vehicle frame having an opening therein, of a brake cylinder device comprising a cylindrical portion insertable in said opening, a flange on said cylindrical portion in supporting engagement with said frame, a pressure head at one end of the cylindrical portion, means anchored in said frame for securing said cylindrical portion to said frame and for clamping said head against said flange, a non-pressure head at the other end of the cylindrical portion, and means anchored in said frame for clamping

the non-pressure head against said cylindrical portion.

3. The combination with a vehicle frame of an annular wall integral with said frame defining a brake cylinder receiving recess, a brake cylinder device comprising a cylindrical portion insertable in the recess defined by said wall, a flange on said cylindrical portion overlapping and engaging the upper end of said wall for supporting said cylindrical portion on said frame, a pressure head at one end of the cylindrical portion, means anchored in said wall for clamping said flange to said wall and the pressure head to the flange, a non-pressure head at the other end of the cylindrical portion, and means anchored in said wall for clamping said non-pressure head against said cylindrical portion.

4. The combination with a vehicle frame, of an annular wall integral with said frame defining a brake cylinder receiving recess, a brake cylinder device comprising a cylindrical portion fitting loosely in the recess defined by said wall, a flange on said cylindrical portion engaging the upper end of said wall and supporting the cylindrical portion on the frame, a pressure head, bolts anchored in said wall extending through said flange and head, nuts on said bolts for clamping said head against said flange, a non-pressure head, and means anchored in said wall for securing said non-pressure head to said cylindrical portion.

In testimony whereof I have hereunto set my hand this twenty-sixth day of August, 1929.

HENRY A. WAHLERT.
